(57) **CLAIM**

The ornamental design for a rear portion of a vehicle, toy replica and/or other replicas, as shown and described.

DESCRIPTION

This application contains subject matter related to the following co-pending application: application Ser. No. 29/334,932, filed on even date herewith, entitled Vehicle, Toy, or Likeness Thereof.

FIG. 1 is a left, front perspective view of a rear portion of a vehicle, toy replica and/or other replicas according to our novel design, the right, front perspective view being mirror symmetrical;

FIG. 2 is a left side view thereof, the right side view being mirror symmetrical;

FIG. 3 is a front view thereof; and,

FIG. 4 is a top view thereof.

The broken lines are for illustrative purposes only and form no part of the claimed design.

1 Claim, 4 Drawing Sheets

FIG. 1

FIG. 3

FIG. 4
